T. OGDEN AND L. WARE.

ROTARY VALVE.

APPLICATION FILED FEB. 24, 1916. RENEWED MAY 3, 1920.

1,360,784.

Patented Nov. 30, 1920.

UNITED STATES PATENT OFFICE.

THOMAS OGDEN AND LAYTON WARE, OF RAWLINS, WYOMING.

ROTARY VALVE.

1,360,784.

Specification of Letters Patent. Patented Nov. 30, 1920.

Application filed February 24, 1916, Serial No. 80,255. Renewed May 3, 1920. Serial No. 378,658.

To all whom it may concern:

Be it known that we, THOMAS OGDEN and LAYTON WARE, citizens of the United States, residing at Rawlins, in the county of Carbon and State of Wyoming, have invented certain new and useful Improvements in Rotary Valves, of which the following is a specification.

This invention relates to improvements in rotary valves.

One object of the invention is to provide such a valve which may be adapted for various purposes, and in which the provision of packing elements to insure against leakage is obviated.

Another object of the invention is to provide a valve of this character which, when used in the place of the conventional form of slide valve for locomotive cylinders, may be plugged so that upon blowing out or breakage of either end of the cylinder, which would ordinarily render the same entirely inoperative, the remaining end thereof may be used to its full capacity.

A further object of the invention is to provide a valve of this character which may be lubricated regardless of the pressure thereagainst, and to provide novel means to accomplish such lubrication.

With the foregoing and other objects in view, the invention consists in the novel features of construction, combination and arrangement of parts, as will be hereinafter more fully described, illustrated in the accompanying drawings and claimed.

In the drawings,

Figure 1 is a transverse section of a locomotive cylinder showing the improved rotary valve mounted thereon.

Fig. 2 is a face view of the valve showing its arrangement with respect to the feed and exhaust ports of the cylinder.

Fig. 3 is a sectional view taken on the line 3—3 of Fig. 1.

Fig. 4 is another sectional view taken on the line 4—4 of Fig. 1.

Fig. 5 is a side elevation of the valve member.

Fig. 6 is a detail perspective view of the valve member.

Referring to the drawings by numerals and more particularly to Figs. 1 and 2, 1 designates a portion of a locomotive which has mounted thereon a cylinder casting 2. This casting is of substantially the usual construction and is provided with a longi-

tudinal bore 3 within which is arranged a piston head 4 for sliding movement.

An enlargement 5 is formed upon the casting 2 above the bore 3 and this enlargement is provided upon its outer face with a substantially rectangularly shaped opening 6 which is adapted to be closed by a plate 7 to form a pocket which may serve, as in the present instance, as steam chest, an opening being provided in one wall of the enlargement in communication with the opening 6 which has communicating therewith a feed pipe 8 which extends from the boiler.

A longitudinally tapered bore 9 is formed in the enlargement 5 with the larger end thereof opening into the pocket or steam chest. This bore is of any desired length and communicates with a straight bore 10 which opens through the inner face of the enlargement.

The improved valve comprises a tapered head 11 of a size and shape to be snugly received by the tapered opening 9, and an elongated shank 12 of uniform diameter to be received by the bore 10, the shank 12 extends any desired distance past the inner face of the enlargement 5 and engages an opening in a lug 13 formed upon the casting. A collar 14 is formed on or may be secured to the shank 12 in any desired manner and between this collar and the inner face of the enlargement is arranged a flat expansion spring 15 which exerts a tension to normally hold the valve in engagement with the tapered bore 9. Also mounted upon the shank 12 is an arm 16 to which is connected a rod 17 which is in turn connected in any suitable manner to the usual link motion for operating the valve.

Ports 18 and 19 are formed in the enlargement 5, said ports opening into the tapered bore 9 at diametrically opposite points therein and one of these ports communicates with bore 3, near the front of the cylinder, while the other port communicates with said bore 3 near the rear end of the cylinder. A third bore 20 is formed in the casting and opens into the bore 9 at a point intermediate the inner open ends of the ports 18 and 19. This port 20 extends through the casting in any desired direction and opens therefrom to provide an exhaust.

Ports 21 and 22 are formed in the head 11 of the valve and these ports open into the outer flat face of the head, being arranged in radial alignment with respect to the center

of the head and being offset with respect to the center of the head, as is illustrated to advantage in Fig. 2 of the drawings. These ports 21 and 22 extend in a longitudinal direction with respect to the valve and are of any desired length, being then extended at right angles to themselves and opening into the outer face of the head. The ports 18 and 19 are offset longitudinally to the bore 9 relative to the port 21, and the ports 21 and 22 are of a length to aline with these ports 18 and 19. Annular grooves 23 and 24 are formed upon the outer face of the head 11 and extend substantially through-out one fourth of its circumference. Each of these grooves is provided at one end with an offset portion 25 which is arranged in alinement with the ports 18 and 19, the grooves 23 and 24 proper being arranged in alinement with the port 20.

By an arrangement of ports as just described, it will be noted that as the valve is oscillated the offset portions 25 of the grooves 23 and 24 will alternately aline with the ports 18 and 19 while the opposite ends of the grooves will alternately aline with the port 20. Also the ports 21 and 22 will alternately aline with ports 19 and 18 respectively. When the port 21 is alined with the port 19 the groove 23 provides a communication between the port 18 and the port 20. Likewise when the port 22 communicates with the port 18 the groove 24 forms a communication between the port 19 and the port 20. It is obvious therefore that when the port 21 is alined with the port 19 the piston head 4 will be moved in one direction, the steam upon its opposite side being exhausted through the port 18, groove 23 and port 20. When the piston reaches the end of its stroke the link motion will operate to move the valve to aline the port 22 with the port 18 and the groove 24 with the port 19 and port 20. This will cause the steam to flow through the port 18 and force the piston head in an opposite direction whereupon the dead steam to its opposite face will be forced through the port 19, groove 24 and out through the exhaust port 20.

Should the cylinder head blow out or become damaged in any manner as to prevent operation of the engine the port 22 may be plugged. This will cause the steam within the pocket or steam chest to act only upon the rear face of the piston in as efficient a manner as would be accomplished were the port 22 open. Likewise the port 21 may be plugged and the forward end of the cylinder will operate to its full capacity.

A recess 26 is formed in the enlargement, said recess 26 communicating with the straight bore 10, while a reduced bore 27 is formed in the enlargement and opens into one outer face thereof and is in communica-

tion with the recess, being normally closed by means of a plug 28. By filling the recess 26 with grease or oil, oscillation of the valve will cause the grease or oil to be distributed over the faces of the valve, and thereby insure its thorough lubrication. In order to prevent this grease or oil from draining from the recess 26 about the shank 12 a packing nut 29 is provided, which nut is threaded into an opening in the inner face 75 of the enlargement and has a packing material arranged to be compressed against the shank.

In Figs. 3 and 4 of the drawings we have shown a valve of substantially the same design as that disclosed in Figs. 1 and 2 of the drawings. This construction serves to adapt the valve for various purposes other than as a valve for feeding steam to locomotive cylinders.

This valve consists of a casing 30 having a longitudinally extending tapered bore 31 within which is arranged the tapered head 32 of the valve, the same being provided with a shank 33 having an angular head 34 in the shape of an isosceles triangle. A handle 35 having an opening therein of a size to snugly receive the angular head 34 is mounted upon the head in any suitable manner and this handle has abutting against its under face a helical expansion spring 36 which is wound about the shank 33 and has one end abutting the casing 30. This spring serves to normally hold the tapered head 32 in engagement with the bore 31. An opening 37 extends longitudinally through a portion of the head and opens into the tapered face thereof, being adapted for alinement with an opening 38 in the side wall of the casing whereby communication may be established between the interior of the casing and the opening 38. A threaded opening 39 is formed in one side of the casing and this opening communicates with the tapered bore 31. A plug may be provided 105 for closing this opening or a grease cup 40 may be threaded therein to supply a lubricant to the wearing surfaces of the valve.

It will be noted that, by the provision of an angular head of isosceles triangular 115 shape, it is impossible to place the handle 35 upon the shank except in one position. This provides means whereby a mark upon the casing may serve as a guide to the operator of the valve so that he may determine 120 the direction and the necessary rotary movement to aline or disaline the openings 37 and 38 to establish or cut-off communication between the interior of the casing and the port 38.

From the foregoing description taken in connection with the accompanying drawings, it is thought that the construction and operation of the improved rotary valve may be clearly understood, and while we have 130

herein shown and described one specific embodiment of our invention, we do not wish to be limited thereto, except for such limitations as the claims may impart.

5 We claim:

1. A valve structure comprising a casing provided with an inlet port and having a valve seat formed therein, delivery ports opening into said seat at points diametrically opposite, an exhaust port opening into said seat at a point intermediate said delivery ports and offset longitudinally of the seat with respect to said delivery ports, a valve plug rotatably mounted in said seat, inlet ports extending longitudinally through said plug, and opening at their outer ends into said casing, the inner ends of said inlet port being extended at an angle to open into the side face of the plug for registration with said delivery ports, and exhaust ports extending circumferentially around said plug, each of said exhaust ports having one end thereof disposed for registration with the exhaust port in said casing and the opposite end thereof extended longitudinally of the valve for registration at times with one of the delivery ports.
2. A valve structure comprising a casing

provided with an inlet port and having a tapered valve seat formed therein, delivery 30 ports opening into said valve seat at points diametrically opposite, an exhaust port opening into said valve seat, at a point intermediate but offset longitudinally from said inlet port, a tapered valve plug rotatably 35 mounted in said seat, inlet ports extending longitudinally through said plug from the larger end thereof and opening into the side face of the plug for registration with the said delivery ports, and a plurality of substantially 40 L-shaped exhaust grooves formed in the tapered face of said plug and having the longer legs thereof extending circumferentially of the plug and disposed for registration with the exhaust port in the casing, 45 the shorter legs of said grooves being extended longitudinally of the plug for registration at times with the delivery port.

In testimony whereof we affix our signatures in presence of two witnesses.

THOMAS OGDEN.
LAYTON WARE.
